(57) **ABSTRACT**

A roadblock for temporary installation to block traffic and/or as a security precaution includes an elongated casing with two opposing longitudinal side walls. The two side walls join an upper wall. At least one casing support structure is located in the elongated casing and connects to both side walls. Supports for resting on the ground/surface are connected to the lower side of the elongated casing and/or the lower side of the casing support structure. Plural stabilization arms protrude from one of the longitudinal side walls and are detachable.

**ROADBLOCK FOR TEMPORARY
INSTALLATION TO BLOCK TRAFFIC
AND/OR AS A SECURITY PRECAUTION**

**CROSS-REFERENCE TO RELATED
APPLICATIONS**

This application is a continuation of U.S. Pat. No. 11,781,274, formerly patent application Ser. No. 17/002,924, filed on Aug. 26, 2020, and issued on Oct. 10, 2023, which claims priority to The Netherlands Patent Application No. 2023715 filed Aug. 27, 2019, which patent and patent applications are hereby incorporated by reference in their entirety.

BACKGROUND OF THE INVENTION

Field of the Invention

The present invention relates to a roadblock for temporary installation to block traffic and/or as a security precaution comprising an elongated casing with two opposing longitudinal side walls, the two side walls joining an upper wall, and at least one casing support structure located in the elongate casing and connected to both the side walls.

Description of Related Art

Roadblocks are temporary installations set up to control or block traffic, e.g., during roadworks, temporary road closure and as a security precaution, such as Hostile Vehicle Mitigation (HVM). The usage demands of such roadblocks are various. Preferably a roadblock is easy to install and remove, as well as easy to transport and store. These demands may, for instance, be provided by an elongated element substantially shaped as a traffic barrier, which traffic barrier may, or may not, be firmly connected to the ground or surface. A further elementary requirement of a roadblock is that it provides an essential blocking functionality as it has to be able to handle the forces exerted on the roadblock exerted by a vehicle that collides with the roadblock. The blocking functionality may be provided by the combination of various technical features like the shape of the roadblock, the weight (mass) of the roadblock, the connection(s) of the roadblock with the surface, and/or one or more roadblock support(s). And even when one or more of the possible mounting assemblies break, disconnect from the roadblock and/or when the mounting assemblies detach from their position due to a considerable force being exerted on the roadblock as a result of the impact of a vehicle onto the roadblock, the roadblock still is required to fulfill a blocking function.

An actual development is that there is an enhanced attention for the blocking functionality of roadblocks as a result of an increased awareness in the protection of public spaces. This increased awareness is, among others, a result of several recent terrorist attacks, wherein vehicles (cars and trucks) were used. The request is thus to further enhance the blocking capabilities of both existing and new roadblocks. A problem is thus to provide a roadblock that is easy in use (e.g., easy to install, easy to remove, easy to transport and/or easy to store) in combination with providing a large blocking effect.

SUMMARY OF THE INVENTION

This problem is solved with a roadblock for temporary installation to block traffic and/or as a security precaution,

2

comprising: an elongated casing with two opposing longitudinal side walls, the two side walls joining an upper wall; at least one casing support structure located in the elongated casing and connecting to both the side walls; supports for resting on the ground/surface connected to the lower side of the elongated casing and/or the lower side of the casing support structure; and plural stabilization arms protruding from one of the longitudinal side walls, wherein the protruding length of the stabilization arms is adjustable. The lower side of the elongated casing and the lower side of the casing support structure (that are thus located opposite to the upper wall) may be open, partially open or closed. In an operative position, the sideward protruding stabilization arms are preferably brought in a longer (or even better, the longest) configuration. In normal practice, it is prescribed to use the roadblock only with the stabilization arms in their longest configuration, as that is the condition wherein the roadblock is tested and approved. In the operative (installed) situation of the roadblock, the stabilization arms will rest with their free ends on the bottom or be a short distance from the bottom. When the roadblock then is substantially impacted (e.g., by a vehicle) on the sidewall from which the stabilization arms protrude, the roadblock may start tilting such that the free ends of the stabilization arms will move upward. With a further forward movement of the vehicle that provides the impact, the upward movement of the arms (or at least some of the arms) will contact the underside of the vehicle, and dependent on the forces, dimensions and weights, the vehicle may be partially lifted from the floor. This will normally stop the vehicle and thus the sought for blocking function is provided. For stopping a vehicle with substantial impact, the roadblock will thus tilt and the tilted roadblock will have resistance to displacement over the floor/underground while simultaneously the vehicle will be lifted by the rotating stabilization arms (as a result of the tilting of the roadblock).

For a proper functioning of the roadblock, the stabilization arms will require a substantial length of approximately 0.5-1.5 m. The disadvantage of the protruding arms is, however, that they are disadvantageous during the handling, transportation and storage of the roadblocks. The present invention, however, enables the length of the stabilization arms to be adjusted so that, during handling, transportation, and storage, the protruding arms may be reduced in their length or even may be absent. This enables a simpler and cheaper handling, transportation, and/or storage of the roadblock according to the present invention without any reduction of functionality.

Preferably, the stabilization arms are parallel orientated so that, independent of the location of impact, the colliding vehicle will always be "caught" by one or more arms. Furthermore, the angle enclosed by the stabilization arms and the longitudinal side wall may be more than 90°, preferably 93°-100°. Such a design further stimulates the "catching" of impacting vehicles.

The stabilization arms may be located opposite the upper wall of the elongated casing, thus on the lower side of the roadblock. The front of an impacting vehicle first has to pass the protruding ends of the stabilization arms before the vehicle will contact the upper wall of the elongated casing. This implies that the stabilization arms will have to be close to the bottom of the floor. Furthermore, the coupling of the stabilization arms on the lower side of the roadblock will provide leverage when the arms are moved upward during the tilting of the roadblock.

There are several alternatives for the adjustment of the protruding length of the stabilization arms. The stabilization

arms may be formed by at least two interchangeable arm segments, for instance, telescopically segmented arms. Another option is that interchangeable arms are completely detachable or that a segmented arm has one or more detachable segments.

The supports may be provided with at least one central protrusion facing away from the elongated casing, which central protrusions are located on the side of a vertical central plane, though the elongated casing is facing away from the longitudinal side wall with the stabilization arms. These central protrusions form the first pivot points during the initial tilting of the roadblock.

The supports may also be provided with at least one second sideward protrusion facing away from the elongated casing, which sideward protrusions are located alongside the elongated casing on the side facing away from the stabilization arms. These second sideward protrusions are forming the second pivot points during further tilting of the roadblock after the initial tilting took place over the central protrusions of the supports and as described in the previous paragraph. To facilitate this change of pivot point during the tilting from the central protrusions to the second sideward protrusions, the central protrusions may protrude further down than the sideward protrusions.

The central protrusions and/or the sideward protrusions may have sharp angles to prevent the roadblock from shifting over the floor after impact. Sharp angled protrusions may grip into the bottom and increase the frictional resistance between the roadblock and the bottom.

The sideward protrusions may also have at least two sharp angles, like some teeth of a gear, so that during further tilting of the barrier, the point of pivoting may be followed from one to the next sharp angle.

As the blocking functionality of the roadblock on the sides is relevant, the ends of the elongated casing may be chamfered. This also prevents the chance of unwanted contact of road users (pedestrians, cyclists, guards) with the roadblock.

To enable coupling of the roadblock with other roadblocks or other objects, the ends of the elongated casing may be provided with couplings.

The roadblock may also be provided with at least one friction-increasing element attached to the upper wall of the elongated casing such that at least one (tapered) contact edge is protruding from a longitudinal side wall of the elongated casing. The advantage of the add on of a friction-increasing element is that when the roadblock to which the friction-increasing element is attached tilts, or is toppled, the tapered contact edge of the friction-increasing element may contact the ground (or surface) the roadblock stood on until the moment of impact. Due to the contact of the (tapered) contact edge, the friction between the frictional resistance between the road barrier and the ground increases due to which the further displacement (shift) of the barrier over the ground is further inhibited or prevented. The cause of this is the local high pressure on the location(s) where the contact edge engages on the ground/floor. The contact edge, e.g., a toothed edge, may "bite" into the ground.

In the roadblock, height adjustable wheels may also be provided. Such wheels may be used for relocation of the roadblock over shorter distances such as during accurate positioning of the roadblock. During use of the roadblock, the wheels have to be lifted to prevent undesired movement of the roadblock with the wheels.

The roadblock may be made from steel as in practice steel sheet material which is easy to obtain at reasonable prices. Also, during production of the prior art traffic barriers and

roadblocks, often use is made of steel plate material, so production of the roadblock according to the present invention will normally fit the production facilities of traffic barrier and roadblock producers without the demand for substantive changes of adaptation.

The roadblock according to the present invention may also be provided with at least one, but preferably at least two, lifting openings to enable to attach a manipulator (e.g., a crane) for installment and/or removal of the roadblock.

BRIEF DESCRIPTION OF THE DRAWINGS

The present invention will be further elucidated on the basis of the non-limitative exemplary embodiments shown in the following figures:

FIG. 1 is a perspective view of a roadblock according to the present invention with a limited length of the stabilization arms;

FIG. 2 is a perspective frontal view of the roadblock shown in FIG. 1 with longer stabilization arms than in the state shown in FIG. 1;

FIG. 3A a side view of the roadblock in the state shown in FIG. 1;

FIG. 3B a side view of the roadblock in the state shown in FIG. 2; and

FIG. 4 is a cut-away view of a part of the interior of the roadblock taken along the line 4-4 of FIG. 3B.

DESCRIPTION OF THE INVENTION

FIG. 1 shows a roadblock 1 with an elongated casing 2 with a longitudinal side wall 3, an upper wall 4 and a chamfered end part 5 with couplings 6. On the lower side of the roadblock 1, supports 8 are attached for resting on the ground/surface and four stabilization arms 9 protrude from the longitudinal side wall 3. On the upper wall 4 are friction-increasing elements 10 attached with fixing bolts 11. In the state represented in FIG. 1, the stabilization arms 9 are collapsed and have only a limited length enabling a relatively simple handling, transportation, and storage of the roadblock 1.

FIG. 2 shows the roadblock 1 shown in FIG. 1 with longer stabilization arms 9 than in the state shown in FIG. 1. As shown in FIG. 2, the stabilization arms 9 are extended and telescopic sliding inner arm segments 12 are moved out of larger outer arm segments 13. The extended position of the inner arm parts 12 is secured by locking pins 14.

FIG. 3A is a side view of the roadblock 1 in the state shown in FIG. 1, thus with collapsed stabilization arms 9. Also visible is a locking pin 14 that secures the "stowed away" inner arm segment 12 in the outer arm segment 13. In this figure also, a better view is provided on a support 8. Support 8 has a sharp angled central protrusion 15 facing downward and the protrusion 15 is located on the side of a (frictional) vertical central plane 16 extending through the roadblock 1 opposite the side of the roadblock 1 with the stabilization arms 9. Support 8 further also has a second sideward protrusion 17 also facing down and this second sideward protrusion 17 is located alongside the elongated casing 2 on the side facing away from the stabilization arms 9. The second sideward protrusion 17 has three sharp angles 18. Also clearly visible is that the central protrusion 15 protrudes further down than the sideward protrusion 17. In FIG. 3B, the side view of roadblock 1 is shown but here, like in FIG. 2, inner arm segment 12 is moved out of larger outer arm segment 13, thus stabilization arm 9 is now in a longer

state. An angle α enclosed by the stabilization arm 9 and the vertical central plane 16 (or the longitudinal side wall 3) is more than 90° .

FIG. 4 shows a cut-away part of roadblock 1 with a part of the interior of the roadblock. A part of a casing support structure 19, which is located in the elongated casing 2, holds a wheel 20 of which the position is adjustable so that wheel 20 may be lowered so far that it protrudes below a lower side 21 of roadblock 1. For adjustment of the position of wheel 20, a bolt coupling 22 is accessible through upper wall 4. As shown most clearly in FIGS. 1 and 2, casing support structure 19 also includes parts 7 protruding from the side wall 3.

The invention claimed is:

1. A roadblock for temporary installation to block traffic and/or as a security precaution, comprising:

an elongated casing with two opposing longitudinal side walls, the two side walls joining an upper wall; at least one casing support structure located in the elongated casing;

supports for resting on the ground/surface connected to the lower side of the elongated casing and/or the lower side of the casing support structure; and

plural stabilization arms protruding from one of the longitudinal side walls;

wherein the protruding length of each of the stabilization arms is adjustable; and

wherein the stabilization arms are detachable.

2. The roadblock according to claim 1, further comprising at least one wheel held by the at least one casing support structure, wherein the position of the wheel is adjustable.

3. The roadblock according to claim 1, wherein the stabilization arms are parallel orientated.

4. The roadblock according to claim 1, wherein the angle enclosed by the stabilization arms and the longitudinal side wall is more than 90° .

5. The roadblock according to claim 1, wherein the stabilization arms are located opposite the upper wall of the elongated casing.

6. The roadblock according to claim 1,

wherein the supports are provided with at least one central protrusion facing away from the elongated casing, which central protrusion is located on the side of a vertical central plane through the elongated casing that is facing away from the longitudinal side wall with the stabilization arms.

7. The roadblock according to claim 1,

wherein the supports are provided with at least one central protrusion facing away from the elongated casing, which central protrusion is located on the side of a vertical central plane through the elongated casing that is facing away from the longitudinal side wall with the stabilization arms, and

wherein the supports are provided with at least one second sideward protrusion facing away from the elongated casing, which sideward protrusion is located alongside the elongated casing on the side facing away from the stabilization arms.

8. The roadblock according to claim 1,

wherein the supports are provided with at least one central protrusion facing away from the elongated casing, which central protrusion is located on the side of a vertical central plane through the elongated casing that is facing away from the longitudinal side wall with the stabilization arms,

wherein the supports are provided with at least one second sideward protrusion facing away from the elongated

casing, which sideward protrusion is located alongside the elongated casing on the side facing away from the stabilization arms, and
wherein the central protrusion protrudes further down than the sideward protrusion.

9. The roadblock according to claim 1,

wherein the supports are provided with at least one central protrusion facing away from the elongated casing, which central protrusion is located on the side of a vertical central plane through the elongated casing that is facing away from the longitudinal side wall with the stabilization arms,

wherein the supports are provided with at least one second sideward protrusion facing away from the elongated casing, which sideward protrusion is located alongside the elongated casing on the side facing away from the stabilization arms, and

wherein the central protrusion and/or the sideward protrusion has sharp angles.

10. The roadblock according to claim 1,

wherein the supports are provided with at least one second sideward protrusion facing away from the elongated casing, which sideward protrusion is located alongside the elongated casing on the side facing away from the stabilization arms, and

wherein the sideward protrusion has at least two sharp angles.

11. The roadblock according to claim 1, wherein the ends of the elongated casing are chamfered.

12. The roadblock according to claim 1, wherein the ends of the elongated casing are provided with couplings.

13. A roadblock for temporary installation to block traffic and/or as a security precaution, comprising:

an elongated casing with two opposing longitudinal side walls, the two side walls joining an upper wall; at least one casing support structure located in the elongated casing;

supports for resting on the ground/surface connected to the lower side of the elongated casing and/or the lower side of the casing support structure; and

plural stabilization arms protruding from one of the longitudinal side walls, each of which stabilization arms includes a telescopic sliding inner arm segment movable out of a larger outer arm segment; wherein the protruding length of each of the stabilization arms is adjustable; and

wherein at least one of the inner arm segments and at least one of the outer arm segments is detachable.

14. The roadblock according to claim 13, further comprising at least one wheel held by the at least one casing support structure, wherein the position of the wheel is adjustable.

15. The roadblock according to claim 13,

wherein the supports are provided with at least one central protrusion facing away from the elongated casing, which central protrusion is located on the side of a vertical central plane through the elongated casing that is facing away from the longitudinal side wall with the stabilization arms,

wherein the supports are provided with at least one second sideward protrusion facing away from the elongated casing, which sideward protrusion is located alongside the elongated casing on the side facing away from the stabilization arms, and

wherein the central protrusion and/or the sideward protrusion has sharp angles.

16. A roadblock for temporary installation to block traffic and/or as a security precaution, comprising:
 an elongated casing with two opposing longitudinal side walls, the two side walls joining an upper wall;
 at least one casing support structure located in the elongated casing;
 at least one wheel held by the at least one casing support structure, wherein the position of the wheel is adjustable;
 supports for resting on the ground/surface connected to the lower side of the elongated casing and/or the lower side of the casing support structure; and
 plural stabilization arms protruding from one of the longitudinal side walls, each of which stabilization arms includes a telescopic sliding inner arm segment movable out of a larger outer arm segment;
 wherein the protruding length of each of the stabilization arms is adjustable; and

wherein at least one of the inner arm segments and at least one of the outer arm segments is detachable.

17. The roadblock according to claim **16**, wherein the supports are provided with at least one central protrusion facing away from the elongated casing, which central protrusion is located on the side of a vertical central plane through the elongated casing that is facing away from the longitudinal side wall with the stabilization arms,

wherein the supports are provided with at least one second sideward protrusion facing away from the elongated casing, which sideward protrusion is located alongside the elongated casing on the side facing away from the stabilization arms, and
 wherein the central protrusion and/or the sideward protrusion has sharp angles.
